DESIGN FOR A LAMP SHADE OR SIMILAR ARTICLE

Earl W. Newton, Chicago, Ill., assignor to Imperial Glass Corporation, Bellaire, Ohio, a corporation of Ohio

Application August 6, 1936, Serial No. 64,278

Term of patent 14 years

To all whom it may concern:

Be it known that I, Earl W. Newton, a citizen of the United States of America, and resident of Chicago, county of Cook, and State of Illinois, have invented a new, original, and ornamental Design for a Lamp Shade or Similar Article, of which the following is a specification, reference being had to the accompanying drawing, forming part thereof, in which—

Figure 1 is a top plan view of a lamp shade or similar article, showing my new design; and

Figure 2 is a side elevational view of the same.

The invention resides in a bell shaped reflector body having an aperture at its diametrical center, and having a plurality of equally spaced spherical projections provided in its peripheral edge.

I claim:

The ornamental design for a lamp shade or similar article substantially as shown.

EARL W. NEWTON.
